UNITED STATES PATENT OFFICE.

HENRY VAN HOEVENBERGH, OF ELIZABETH, NEW JERSEY.

PRINTING-TELEGRAPH.

SPECIFICATION forming part of Letters Patent No. 292,966, dated February 5, 1884.

Application filed April 30, 1883. (No model.)

To all whom it may concern:

Be it known that I, HENRY VAN HOEVENBERGH, a citizen of the United States and a resident of Elizabeth, in the county of Union and State of New Jersey, have invented certain new and useful Improvements in Printing-Telegraphs, of which the following is a specification.

My invention relates to certain improvements in the construction and organization of apparatus and circuits for printing-telegraphs; and it especially pertains to the construction of transmitting devices for multiple-wire instruments.

The object of my invention is to provide means for neutralizing the effects of the so-called "static currents," which occur at the cessation of the electric impulses employed for actuating the receiving-instruments to effect a more reliable operation of the impression-lever and to obtain a more rapid movement of the type-wheel. To effect this result, the polarity of each succeeding current or impulse which is transmitted to the receiving-instrument is reversed with reference to the preceding impulse traversing the same conductor.

The invention consists in combining with a rotating armature and a series of electro-magnets, respectively, included in a series of line-conductors, a transmitting device organized to alternately connect the respective poles of a battery with the corresponding terminals of the line-conductors in succession.

In carrying out my invention I prefer to employ a revolving pole-changer of any suitable construction, arranged to alternately connect the positive and negative poles of the transmitting-battery with the earth, and to simultaneously connect the pole which is not in connection with the earth with three contact-arms bearing upon the periphery of a revolving polygonal cam. This cam is revolved by the movement of the pole-changer, and its projecting angles force the contact-arms outwardly in succession, thereby causing each of them in turn to impinge against a corresponding one of three contact-springs. These contact-springs are respectively connected with three line-conductors extending to the receiving-station. An electro-magnet is included in each of the line-conductors at the receiving-

station, and these electro-magnets, being successively vitalized by the impulses caused to traverse the line-conductors, serve to revolve an armature in one direction or the other, according to the order of succession in which the electro-magnets are vitalized.

The accompanying drawing is a diagram illustrating an organization of apparatus and circuits embodying my invention.

Referring to the figure, A and B respectively represent a transmitting and a receiving station of a printing-telegraph system, and L' L² L³ represent three line-conductors uniting the same.

At the transmitting-station is located a battery, E, and a pole-changing device, C. The pole-changer C consists of two contact-wheels mounted side by side upon an arbor, C'. The peripheries of each of the wheels are divided into insulated conducting-segments. The alternate contact-segments of one wheel are united with each other, and by a conductor, 1, with the positive pole of the battery E. The remaining contact-segments of the wheel are likewise electrically connected with each other and with a conductor, 2, leading to the negative pole of the battery E. The alternate conducting-segments of the other wheel are likewise connected, through the conductors 1 and 2, with the positive and negative poles, respectively, of the battery E. Two contact-brushes, F' and F², respectively, rest against the peripheries of the two wheels, and they are so adjusted that, while the brush F' is electrically connected with the negative pole of the battery E, the brush F² will be likewise connected with the positive pole, and vice versa. Thus by the revolution of the pole-changing device C the brushes F' and F² will be alternately connected with the positive and negative poles of the battery. The brush F' is connected by a conductor, 3, with the earth at G and the brush F² by conductor 4 with three contact-arms, h', h², and h³.

A polygonal cam, H, is mechanically united with the arbor D and revolved thereby through two suitable gear-wheels, I and i. Against the periphery of this cam the three contact-arms h are caused to impinge.

In the drawing I have shown the polygonal cam H as having five sides. It is so organ-

ized with reference to the pole-changer C that for each reversal of the battery E, occasioned by the movement of the pole-changer, the cam will complete one-fifteenth of a complete revolution. The contact-arms h are so arranged relatively to the periphery of the cam H that only one of the same will impinge against a projecting angle of the cam at a time, and that they will be forced outward in succession by passing over such an angle. The organization is further so adjusted that one of the arms h will be thus forced outward by one of the angles of the cam at each reversal of the poles of the battery E with reference to the brush F. 15 Three contact-springs, P' , P^2 , and P^3 , respectively, extend into such proximity to the arms h' , h^2 , and h^3 that when either arm is forced outward by an angle of the cam H passing beneath its extremity, a point, o, carried thereon 20 will impinge against the corresponding spring, P , thereby completing a circuit from the brush F^2 to that particular contact-spring. The contact-springs P' , P^2 , and P^3 are respectively electrically connected with the three line-conductors L' , L^2 , and L^3 . It will be seen thus that if the pole-changer C be revolved by means of the crank N or other suitable device, the positive pole of the battery E will first be connected, through wire 2, brush F' , and conductor 3, with 25 the earth at G. The negative pole will be simultaneously connected, through the conductor 1, brush F^2 , conductor 4, and one of the contact-arms h —for example, h' —with the corresponding contact-spring P' , and thus with the line-conductor L' . The further movement of the 30 pole-changer C will cause the negative pole of the battery E to be connected through the conductor 1, brush F' , and conductor 3 with the earth at G, and the positive pole be connected 35 with the wire 2, brush F^2 , conductor 4, and the succeeding arm h^2 with the corresponding contact-spring, P^2 , and conductor L^2 . The further movement of the pole-changer C will establish similar electrical connections from 40 the positive pole of the battery E to the earth at G, and from the negative pole to the conductor L^3 . The continued rotation of the pole-changer will cause these connections to be repeated, with the exception that the polarity 45 of each current or impulse transmitted through any conductor will be opposite to that of the preceding impulse transmitted through the same conductor. The successive positive and negative impulses thus transmitted through 50 the several conductors act to neutralize the static currents which succeed each interruption of the current traversing that conductor, in a manner well understood. At the receiving-station the impulses thus transmitted are 55 employed for actuating a type-wheel, T, through the agency of an armature, R. This armature consists of a disk, D, carried upon an arbor, R', and provided with a series of equidistant radial projections, r' , r^2 , and r^3 , &c. Adjacent to these projections are three 60 electro-magnets, M' , M^2 , and M^3 , respectively

included in the circuits of the conductors L' , L^2 , and L^3 . The electro-magnets M will be successively vitalized by the currents caused to traverse the conductors L, and act to rotate 70 the armature R in one direction or the other, according as they are successively vitalized in the order $M' M^2 M^3$ or $M^3 M^2 M'$. This is accomplished by arranging the projections r with reference to the poles of the electro-magnets M in such manner that at the momentary one projection— r' , for example—confronts the pole of the magnet M' , another projection— r^2 , for example—is within the field of force of the succeeding electro-magnet, M^2 , but not at its 80 nearest point of approach to that pole. If, therefore, the electro-magnet M' be demagnetized and the electro-magnet M^2 vitalized, the armature R will be revolved in the direction indicated by the arrow x' , and a projection, r^3 , will be brought into the same relation with reference to the magnet M^3 , as first described with reference to the projection r^2 and electro-magnet M^2 . A succeeding impulse transmitted through the electro-magnet M^3 90 will further advance the armature R in the direction indicated by the arrow x' , and the same operation will be repeated by the succeeding impulses. The movement of the armature R in the opposite direction is occasioned in precisely the same manner when the electro-magnets are vitalized in the reverse order. 95

For the purpose of effecting an impression, when the type-wheel has been caused by the 100 revolution of the armature R to bring a required type into position, I employ an electro-magnet, N, having three coils, n' , n^2 , and n^3 , respectively included in the circuit of conductors $L' L^2 L^3$. So long as the impulses transmitted over the conductors L are of alternating polarity, the armature N' of this electro-magnet, which may be employed in any suitable manner for effecting the impression of the type, will not be actuated, owing to the magnetic inertia of its core. If, however, any one of the impulses caused to traverse any of the conductors L be prolonged, it will act to induce in the core of the electro-magnet N sufficient magnetism to actuate the armature and 105 effect the impression. Thus, if the pole-changing or transmitting wheel C be rotated until the required number of impulses have been transmitted for bringing any required type into position, the electro-magnet N will 110 be vitalized by arresting the movement, and an impression will then be effected. 115

Any of the well-known devices applicable thereto may be employed for enabling the transmitting-operator to determine the position of the type-wheel, and for maintaining a unison in the positions of the transmitting and receiving devices. 120

I claim as my invention—

1. The combination, substantially as hereinbefore set forth, of a battery, a motor-armature, a series of electro-magnets for actuating 125

said armature, a series of electric conductors respectively including the coils of said electro-magnets, and means, substantially such as described, for transmitting electric currents from 5 said battery upon each of the conductors in succession, and for reversing the polarity of each succeeding current thus transmitted.

2. The combination, substantially as hereinbefore set forth, of a battery, a series of 10 electro-magnets, a series of electric conductors in which the coils of said electro-magnets are respectively included, and means, substantially such as described, for transmitting electric impulses from said battery upon each of the 15 said conductors in succession, and for causing the impulses transmitted upon each conductor to be of the opposite polarity or direction from that of the preceding impulse transmitted upon the same conductor.

20 3. The combination, substantially as hereinbefore set forth, of a battery, a series of line-conductors, means for transmitting electric impulses of alternate positive and negative polarity upon said conductors in recurring 25 succession, an electro-magnet constructed with a series of independent coils, which coils are respectively included in the circuits of said line-conductors, and an armature applied to said electro-magnet, and responding only to a prolonged impulse transmitted through one or 30 more of said coils.

4. The combination, substantially as hereinbefore set forth, of a battery, a pole-changing device, a series of electric conductors, a series of circuit-closers respectively applied thereto, 35 and means, substantially such as described, operated by the movement of said pole-changing device to actuate one of said circuit-closing devices at each reversal of said battery through the action of said pole-changing device. 40

5. The combination, substantially as hereinbefore set forth, of a revolving pole-changer, a revolving polygonal cam mechanically connected therewith, a series of contact-springs, 45 and a series of contact-arms successively caused to impinge each against one of said contact-springs by the action of said cam.

6. The combination, substantially as hereinbefore set forth, of a revolving pole-changer, a 50 polygonal cam, three contact-arms respectively impinging upon the peripheries of said cam, and three contact-springs, against which said contact-arms are successively caused to impinge by the action of said cam. 55

In testimony whereof I have hereunto subscribed my name this 25th day of April, A. D. 1883.

HENRY VAN HOEVENBERGH.
